ATTYS.

UNITED STATES PATENT OFFICE.

CORNELIUS B. O'BLENESS, OF COLUMBUS, OHIO.

IRONING-BOARD.

969,112.

Specification of Letters Patent. Patented Aug. 30, 1910.

Application filed November 9, 1909. Serial No. 527,033.

To all whom it may concern:

Be it known that I, CORMELIUS B. O'BLENESS, a citizen of the United States, residing at Columbus, in the county of Franklin and State of Ohio, have invented a new and useful Improvement in Ironing - Boards, of which the following is a specification.

This invention relates to ironing boards and more particularly to combined ironing and bosom boards, the object being to provide a pair of boards so connected that each one of the boards can be used as desired, and one in which the board not in use serves as a base to support the board being used.

Another object of my invention is to connect the boards so that they can be readily detached so that they can be put into a small place.

With these objects in view, the invention consists in the novel features of construction, hereinafter fully described and pointed out in the claim.

In the drawings forming a part of this specification:—Figure 1 is a perspective view of my improved ironing board. Fig. 1^a is a perspective view of the bosom board detached. Fig. 2 is a side view of my improved board partly broken away. Fig. 3 is a perspective view of the supporting member. Fig. 4 is a perspective view of the bosom board detached. Fig. 5 is an inverted perspective view of the ironing board.

Referring to the drawing A indicates an

ironing board, provided with guide brackets 35 A', in which the foot B', of the standard B is adapted to fit. The standard is provided with a cross-arm B², at its upper end which is adapted to fit in the guide bracket C', of the bosom board C, and securely support 40 the same. The end of the arm B², projects out beyond the end of the board and can be used for an iron support when desired.

From the foregoing description it will be readily seen that I have provided a very 45 novel ironing board which can be easily and quickly put together and one which can be readily reversed so that either of the boards can be used desired.

Having thus fully described my invention, what I claim as new and desire to secure by Letters Patent is:—

As a new article of manufacture an ironing board comprising a standard provided with a foot piece at its lower end and a 55 cross bar at its upper end and ironing boards provided with guide brackets adapted to receive said foot piece and one arm of said cross bar for holding said boards spaced apart in an operative position, the other arm of said cross bar projecting outwardly beyond the end of said board forming an iron support. 60

CORNELIUS B. O'BLENESS.
